UNITED STATES PATENT OFFICE.

ANDRUS S. WEAVER, OF JOY, NEW YORK.

CAR-COUPING.

SPECIFICATION forming part of Letters Patent No. 596,195, dated December 28, 1897.

Application filed July 13, 1897. Serial No. 644,389. (No model.)

To all whom it may concern:

Be it known that I, ANDRUS S. WEAVER, a citizen of the United States, residing at Joy, in the county of Wayne and State of New York, have invented certain new and useful Improvements in Car-Couplers, of which the following is a full and complete specification, such as will enable those skilled in the art to which it appertains to make and use the same.

10 This invention relates to car-couplers; and the object thereof is to provide an improved device of this class which is simple in construction and operation and which is adapted to be connected with both ends of a car, the 15 operation of coupling the cars being automatic and the couplers being adapted to be locked or unlocked from the side or top of the car.

20 The invention is fully disclosed in the following specification, of which the accompanying drawings form a part, in which—

Figure 1 is a bottom plan view of the end of a car provided with my improved coupler; Fig. 2, a partial central longitudinal section 25 of the coupler and showing the supports thereof also in section; Fig. 3, a sectional end view of a part of the coupler; Fig. 4, a plan view of a coupler-head and the parts connected therewith, partly in section, and showing in 30 dotted lines the position it occupies when the car is uncoupled; Fig. 5, a plan view showing the coupler-head in the reverse position; Fig. 6, a back view of a movable jaw which is connected with the coupler-head, and Fig. 7 a 35 section on the line 77 of Fig. 5.

In the drawings forming part of this specification the separate parts of my improvement are designated by the same numerals of reference in each of the views, and in the practice of my invention I provide a coupler which 40 comprises a coupler-head 7, which is provided with an outwardly and forwardly directed stationary jaw 8 at one side and at the opposite side with a forwardly-directed stationary jaw 45 9, with which a movable jaw 10 is connected.

The coupler-head 7 is provided with a backwardly-directed shank 11, and the stationary jaw 9, adjacent to said shank, is provided centrally with an opening 12, which extends there-through and which opens between the movable jaw 10 and the stationary jaw 8.

The movable jaw 10 is provided with a top

plate 13, which is connected therewith by a bolt or pin 14 and a pivot-pin 15, by which the movable jaw is connected with the stationary jaw 9, and said plate 13 is curved to correspond with the shape of the stationary jaw 9 of the coupler-head and rests upon the coupler-head and said jaw, as shown in Figs. 2 and 5. The movable jaw 10 is also provided centrally with a backwardly-directed arm 16, which is of the form shown in Figs. 4 and 6, and the free end thereof is provided with a curved head 17, which is beveled to correspond with the inner wall of the opening 12 in the coupler-head, and said arm 16 is provided with a forwardly-directed cam or projection 10^a and with a backwardly-directed projection 18, on which is formed a head 19, which is provided with an upwardly and rearwardly directed shoulder or projection 20, and the outer ends of the head 19 and of the shoulder or projection 20 are cam-shaped in form, as clearly shown in Figs. 4 and 6, for the purpose of raising the head 27 of the sliding bar 26 in the operation of coupling the cars.

The shank 11 of the coupler-head passes backwardly through a hanger 21, secured to the end of the car, and which is provided with downwardly-directed jaws 22, which are provided with backwardly-directed arms 23, which support an antifriction-roller 24, on which the shank 11 of the coupler-head rests, and that portion of said shank 11 between the jaws 22 of the hanger is wider than the rear end thereof, and formed therein is a slot 25, in which is mounted a sliding bar 26, which is provided at its outer end with a head 27, which passes into the opening 12 of the coupler-head, and the head 27 of the sliding bar 26 is preferably circular or elliptical in form, as shown in Fig. 2, and is provided at the lower side thereof with an outwardly-directed head 28 and at the front side thereof with projections 29 and 30, and these projections are adapted to interlock with the head 19, formed on the backwardly-directed extension 18 of the arm 16 of the movable jaw, and the upwardly and rearwardly directed shoulder or projection 20, formed on said head, and in this operation the movable jaws on the adjacent couplers operate in connection with the cams or projections 10^a and the plates 13 and force the arms 16 backwardly,

as will be readily understood, in such manner as to allow the bar 26 and the head 27 to engage the cam-shaped shoulder or projection 20 of the head 19.

5 Formed in the bottom of the plate 13, which is connected with the movable jaw 10 and which rests on the stationary jaw 9 of the coupler-head, is an irregular chamber 31, which is shown in dotted lines in Fig. 5, and 10 in which is mounted a spring 32, which is also shown in dotted lines in said figure, and the free end of the spring bears on a pin 33, which is secured to the stationary jaw 9, and the operation of the spring 32 is to throw the 15 movable jaw 10 outwardly, as shown in dotted lines in Fig. 4.

Passing through the hangers 34, secured to the bottom of the car at each side thereof is a shaft 35, which is provided at each end 20 with a crank 36, and the shaft 35 passes through the shank 11 of the coupler-head and through an oblong cavity or recess 37 formed in a head 38 at the rear end of the sliding bar 26, and the shaft 35 is provided 25 with a cam 39, and by turning said shaft the bar 26 may be forced outwardly or inwardly, as will be readily understood, the said cam 39 operating on the forward or rear walls of the cavity or recess 37 when the movable jaw 30 10 of the coupler-head is in the position shown in Figs. 1, 2, and 4.

If the sliding bar 26 be forced backwardly by the cam 39 on the shaft 37, the head 27 will be disengaged from the cam 20 on the 35 head 19 of the projection 18 of the arm 16 of the knuckle, and the knuckle, together with the arm 16, will immediately be forced into the position shown in dotted lines in Fig. 4 by the spring 32, in combination with the 40 plate 13 and pin 33, and it will be understood that when the said head 19 or cam 20 formed therein is released from the head 27 of the bar 26 and the knuckle assumes the position above referred to the shaft 35 is again operated and the said sliding bar 26 is forced forwardly by the cam 39, and when the cars come together in the act of being coupled the knuckle 10 of the one car will engage with projection 10^a and plate 13 of the knuckle of 45 the other car and force the same backwardly, and the cam 20 on the head 19 will raise the head 27 on the sliding bar 26 and will pass beneath the same, and the said head will drop down behind said cam 20 on the head 19 and 50 securely lock the knuckle in the position shown in Figs. 1, 4, and 5, and thereby lock the cars together, as will be readily understood.

The rear end of the shaft 11 of the coupler- 60 head passes backwardly through a casing 40, formed on or secured to the plate 41, which is adapted to be secured to the bottom of the car, and said casing is provided at the front end thereof with an upwardly-directed 65 tension 42, in which are mounted two transverse rollers 43, the shafts of which move in slots 44, formed in the sides of the casing in

which said rollers are mounted, and the said rollers 43 project slightly below the base-plate 41 of the casing 40, and the shaft 11 of the coupler-head is provided on its under side with a longitudinal slot 45, which is deepest at the center and the depth of which gradually decreases in the direction of each end thereof, as clearly shown in Fig. 2, and I also provide a locking-lever 46, which is provided with a flat spoon-shaped head 47, which is provided centrally of the upper side thereof with a longitudinal slot 48, which opens forwardly and which extends backwardly approximately to the rear end of the head 47, and mounted in the slot 48 is a friction-roller 49, which is provided with trunnions 50, which rest in bearings 51, formed in the head 47 at each side of said slot 48. 85

Mounted between the rear end of the lever 46 and a suitable bearing 52, secured to the bottom of the car, is a strong expansive spring 53, and in the operation of the device the shank 11 of the coupler-head is free to slide 90 within certain limits between the rollers 43 and the roller 49; but it will be observed that the roller 49 cannot be detached from its position by reason of the manner in which it is supported and by reason of the spring 53, 95 which operates to force the rear end of the lever 46 downwardly, and the head of said lever can only move within certain limits, and when backward pressure is applied to the coupler-head and through said coupler-head to the shank 11, which occurs when the cars are coupled, said shank will move backwardly to a predetermined extent, but cannot move far enough to throw the roller 49 out of the slot 45 in the bottom thereof, and 100 when the weight of the car is thrown on the shaft 11, which occurs when the train is in motion, said shaft 11 of the coupler-head will move forwardly within certain limits, but cannot move far enough to allow the roller 105 49 to be thrown out of the slot 45, and it will thus be seen that the shank 11 of the coupler-head is free to move between the rollers 43 and the roller 49 only within certain limits, this movement being sufficient to compensate 110 for the recoil of the coupler-heads when the cars are coupled and to permit said coupler-heads to move slightly in their supports when the train is being started, and also to allow for the free movement of the coupler-heads 115 when the train is in motion. 120

The lever 46 is supported by inwardly-directed shoulders or projections 54 on the opposite sides of the casing 40, which enter corresponding cavities or recesses in the bottom 125 of the head 47 of the lever 46, and it will be understood that the coupler-heads connected with each end of each car are of the same form and construction, and the movable jaws 130 10 of the coupler-heads at each end of the car are, when said cars are not coupled, held in the position shown in dotted lines in Fig. 4 by the springs 32, and whenever it is desired to couple the cars the shafts 35 are turned for-

wardly or outwardly and the cars are then run together in the usual manner and the movable jaws of the adjacent couplers interlock, and said movable jaws 10 cause the rearwardly-directed arms 16 to rotate or move backwardly, and the cam-shaped heads 19 are forced under the heads 27 of the sliding bars 26 and cause the movable jaws 10 to interlock, as hereinbefore described, when they will occupy the position shown in full lines in Figs. 1, 4, and 5, and it will be apparent that the shaft 35 may be operated from the top of the car, if desired.

My improved coupler is simple in construction and operation and is well adapted to accomplish the result for which it is intended, and it will be apparent that changes in and modifications of the construction herein described may be made without departing from the spirit of my invention or sacrificing its advantages.

Having fully described my invention, I claim as new and desire to secure by Letters Patent—

25 1. In a car-coupler, a knuckle pivotally mounted in the stationary jaw of a draw-head, a curved arm secured thereto and provided with a projecting arm having a cam-shaped shoulder or projection formed therein, a locking-lever mounted in said draw-head and adapted to engage said cam-shaped shoulder or projection, and a plate mounted on said knuckle and projecting over said cam-shaped shoulder and the outer end of said locking-lever, and means for operating the knuckle for the purpose set forth.

2. In a car-coupler, a knuckle pivotally mounted in the stationary jaw of a draw-head, a curved arm secured thereto provided with a forwardly-directed cam or projection formed on or attached thereto, and also provided with a projecting arm having a cam-shaped shoulder or projection formed therein, a locking-lever mounted in said draw-head and adapted to engage said cam-shaped shoulder or projection, and a plate mounted on said knuckle which is provided with a spring mounted thereon, said plate projecting over said cam-shaped shoulder and the outer end of said locking-lever, and means for operating the knuckle for the purpose set forth.

3. In a car-coupler, a knuckle pivotally mounted in a stationary jaw of the draw-head, a curved arm secured thereto and provided with a projecting arm having a cam-shaped shoulder or projection formed therein, and a locking-lever mounted in said draw-head and adapted to engage said cam-shaped shoulder or projection, said locking-bar being pivotally and slidably mounted in said draw-head and adapted to be raised by the said cam-shaped shoulder or projection formed on the curved arm of the knuckle and means for sliding said locking-bar and a plate mounted on said knuckle above said curved arm and locking-lever, and a spring mounted on said plate and adapted to hold the knuckle in an

unlocked position, substantially as and for the purpose described.

4. A car-coupler, comprising a coupler-head, provided with two stationary jaws, and a movable jaw pivotally connected with one of the stationary jaws, one of said stationary jaws being also provided with an opening which extends therethrough, and opens forwardly and backwardly, and said movable jaw with an arm which is adapted to be thrown backwardly into said opening, and on which is formed a backwardly-directed projection, said coupler-head being also provided with a backwardly-directed shank, and at one side thereof with a longitudinally-movable bar which is provided with a head which is adapted to enter said opening, and to engage with said backwardly-directed projection, and means for operating said longitudinally-movable bar from either side of the car, and a casing connected with the bottom of the car through which the shaft of the coupler-head passes, said casing being provided with friction-rollers which are mounted within the upper side thereof, and with a locking-lever which is provided with a head in which is mounted a friction-roller which operates in a groove formed in the bottom of said shank, substantially as shown and described.

5. A car-coupler comprising a coupler-head provided with two stationary jaws, and a movable jaw pivotally connected with one of the stationary jaws, one of said stationary jaws being also provided with an opening which extends therethrough, and opens forwardly and backwardly, and said movable jaw with an arm which is adapted to be thrown backwardly into said opening, and on which is formed a backwardly-directed projection, said coupler-head being also provided with a backwardly-directed shank, and at one side thereof, with a longitudinally-movable bar which is provided with a head which is adapted to enter said opening, and to engage with said backwardly-directed projection, and means for operating said longitudinally-movable bar from either side of the car, and a casing connected with the bottom of the car through which the shaft of the coupler-head passes, said casing being provided with friction-rollers, which are mounted within the upper side thereof, and with a locking-lever which is provided with a head in which is mounted a friction-roller which operates in a groove formed in the bottom of said shank, said shank being passed between the rollers mounted in the upper part of said casing, and the roller mounted on the head of said lever, and a spring by which the rear end of said lever is depressed, substantially as shown and described.

6. A car-coupler constructed as herein described and provided with a shank which passes through a casing or support secured beneath the car, said casing being provided with a friction roller or rollers in the upper side thereof, and with a spring-operated le-

ver in one end of which a friction-roller is mounted, and the shank of the coupler being also provided in the bottom thereof with a cam-groove in which said last-named roller operates, substantially as shown and described.

7. A car-coupler constructed as herein described and provided with a shank which passes through a casing or support secured beneath the car, said casing being provided with a friction roller or rollers in the upper side thereof, and with a spring-operated lever in one end of which a friction-roller is mounted, and the shank of the coupler being also provided in the bottom thereof, with a cam-

groove in which said last-named roller operates, and said car being also provided at the end thereof with a hanger through which the shank of the coupler passes, and with a roller on which said shank rests, substantially as shown and described.

In testimony that I claim the foregoing as my invention I have signed my name, in presence of the subscribing witnesses, this 8th day of July, 1897.

ANDRUS S. WEAVER.
